UNITED STATES PATENT OFFICE

156,175

DESIGN FOR A SPRAY NOZZLE

Fred S. Rosenthal, Chicago, Ill.

Application January 31, 1948, Serial No. 144,205

Term of patent 7 years

(Cl. D91—1)

To all whom it may concern:

Be it known that I, Fred S. Rosenthal, a citizen of the United States, a resident of Chicago, in the county of Cook, State of Illinois, have invented a new, original, and ornamental Design for a Spray Nozzle, of which the following is a specification, reference being had to the accompanying drawing, forming a part thereof:

Fig. 1 is a side elevational view of a spray nozzle embodying my new design;

Fig. 2 is a front view;

Fig. 3 is a rear view of the nozzle; and

Fig. 4 is a cross-sectional view taken along the line 4—4 of Fig. 1.

I claim:

The ornamental design for a spray nozzle, as shown.

FRED S. ROSENTHAL.
